UNITED STATES PATENT OFFICE.

MARK E. BATES, OF LIBERTY, INDIANA.

DESIGN FOR A STATION-INDICATOR OR SIMILAR ARTICLE.

43,296.

Specification for Design.

Patented Dec. 3, 1912.

Application filed August 25, 1911. Serial No. 646,070. Term of patent 7 years.

To all whom it may concern:

Be it known that I, MARK E. BATES, a citizen of the United States, residing at Liberty, in the county of Union and State of Indiana, have invented a new, original, and ornamental Design for Station-Indicators or Similar Articles, of which the following is a specification, reference being had to the accompanying drawing, forming part thereof.

The figure is a view in front elevation of a station indicator, showing my new design.

I claim:—

The ornamental design for a station indicator or similar article, as shown.

In testimony whereof I affix my signature in presence of two witnesses.

MARK E. BATES.
